KNITTING MACHINE

Thomas S. Hayhurst, Belle Harbor, N. Y., assignor
to Max Nydegger, Summit, N. J.

Application April 13, 1944, Serial No. 530,765

40 Claims. (Cl. 66—63)

The present invention relates to an improvement in knitting machines. Objects of said invention have been to provide improved mechanism for the selection of push jacks to control the conditioning of needles in knitting machines, more particularly of the links-links or knit-purl type; to provide jacquard mechanism capable of operating automatically on a high speed multi-unit machine; and to provide needle conditioning mechanism whereby selective individual needle control devices may be made to cooperate effectively with widening and narrowing and other operations involving needle selection.

One embodiment of said invention in a form adapted for use in an automatic multiple flat links knitting machine is described in the following specification and illustrated in the appended drawings, wherein:

Figure 1 is a front elevation of a knitting machine embodying the improved jacquard change or push jack selecting mechanism;

Figure 2, a view partly in plan and partly in horizontal section of parts at the right-hand end of the machine as viewed in Figure 1;

Figure 3, an enlarged view, in front elevation and with parts broken away, of a portion of the machine at the right-hand end of Figure 1;

Figure 4, an enlarged transverse vertical section on the line 4—4 of Figure 2;

Figure 5, a transverse vertical section on the line 5—5 of Figure 2;

Figure 6, an enlarged fragmentary plan view of portions of the needle beds with stitch cams, needle jacks, and needle and jack actuating devices;

Figure 7, a fragmentary view partly in vertical section illustrating the relative positions of the push-in bar and three differently conditioned push jacks, when the push-in bar is at neutral position, said push jacks being conditioned for links-links, straight knitting, and for idling respectively;

Figure 8, an enlarged fragmentary transverse vertical section on the line 8—8 of Figure 6;

Figure 9, a view in elevation of a typical profile or jacquard bar forming part of the needle jack conditioning mechanism;

Figure 10, a portion of Figure 5 further enlarged to more clearly show parts of needle jack conditioning devices in relation to the needle jacks;

Figure 11, a view partly in longitudinal vertical section on the line 11—11 of Figure 10 and with portions broken away and with some parts removed;

Figure 12, a horizontal section on enlarged scale on the line 12—12 of Figure 10;

Figure 13, a horizontal section on enlarged scale on the line 13—13 of Figures 10 and 11;

Figure 14, an enlarged front elevation, with parts in longitudinal vertical section and other parts broken away, showing more clearly jacquard shaft actuating devices at the left end of the machine shown in Figure 1, jack positioning devices and stitch length setting devices;

Figure 15, a fragmentary enlarged view of a portion of the free end of the rod pusher for selectively actuating the profile and fashioning bars and the gathering bar;

Figure 16, a fragmentary plan view partly in horizontal section on the line 16—16 of Figure 14;

Figure 17, a development of the operative surface of locking bar cam 334, Figure 14;

Figure 18, a graph of a cycle of locking bar operation in relation to a cycle of push-in bar movement incident to jacquard change;

Figure 19, a graph of a cycle of profile and gathering bar operation in relation to a cycle of push-in bar movement incident to jacquard change;

Figure 20, a transverse vertical section on the line 20—20 of Figure 14;

Figure 21, a horizontal section on the line 21—21 of Figure 20;

Figure 22, a transverse vertical section on the line 22—22 of Figure 14;

Figure 23, a transverse vertical section on the line 23—23 of Figure 14;

Figure 24, a simplified section illustrating the relative positions of the parts shown when a main jack is raised by the gathering bar to condition the push jack and needle jack for links-links operation;

Figure 25, a view in side elevation of the main jack;

Figure 26, a view in side elevation of the connecting jack;

Figure 27, a view in perspective of the cross jack;

Figure 28, a simplified section illustrating the relative positions of the parts when a main jack and corresponding push jack are conditioned for straight knitting;

Figure 29, a simplified section illustrating the relative positions of the parts shown when a main jack is raised to links-links position by a profile bar while other jacks may be held in straight knitting position by the gathering bar.

Figure 30, a simplified section illustrating the

relative positions of the parts shown when the locking bar is in "down" position;

Figure 31, a simplified section illustrating the relative positions of the parts when the locking bar is in intermediate or change position and the main jacks are free to be moved upwardly, the selector bar being shown in raised position to engage and lift a profile bar.

Figure 31—A, a fragmentary view of parts as shown in Figure 31 and with a lift plate raised to an intermediate main jack lifting position by the selector bar;

Figure 31—B, a view similar to Figure 31—A with the lift plate raised to a higher main jack lifting position;

Figure 32, a simplified section illustrating the relative positions of the parts where the main jack is lifted but the interposed jack has been displaced by the cross jack so that the push jack is conditioned for idling the corresponding needle jack and needle;

Figure 33, a fragmentary view on the line 33—33 of Figure 2 showing a portion, including the control links, of the jacquard operating shaft control mechanism in neutral position;

Figure 34, a view similar to Figure 33 but with one control link in a jacquard change effecting position;

Figure 35, a fragmentary view on the line 35—35 of Figure 2 showing the control link which operates with another similar link in the automatic control of selector bar positioning devices;

Figure 36, a fragmentary view on the line 36—36 of Figure 2 showing the control link associated with the automatic widening and narrowing devices employed in gusset forming operation or the like; and

Figure 37, a fragmentary view on the line 37—37 of Figure 2 showing the control link associated with the automatic widening and narrowing control devices employed in fashioning.

Said mechanism includes devices for determining which needles and their needle jacks shall operate or be active in any course or courses and for controlling the extent to which the selected active needles or selected ones or groups thereof will be pushed in toward stitch cam engaging position. This determines for example whether said active needles are to knit one course or successive courses repeatedly in one bed or the other (straight), or alternate courses in each bed (links-links).

In producing a knitted fabric of uniform width, the group of needles necessary thereto is selected by said devices; and the character of the fabric or its intrinsic pattern is determined in part by the concurrent selection of some or all of said group of needles for links-links and/or for straight knitting, respectively.

In producing certain fabrics, selection is also made where edge or end needles are progressively idled, as in narrowing for fashioning, or in forming gussets; and said needles are restored to operation again either progressively in widening for fashioning; or are all returned in two courses, as in forming gussets.

In narrowing, a further selection is also made of the end needles from which stitches are to be transferred by decking devices prior to their being dropped or rendered inactive by said progressive idling.

Certain features of the selecting mechanism for needle positioning are employed in producing both kinds of fabric (uniform width and fashioned),

while other features are more particularly used in making one or the other of said fabrics.

The selections or determinative positionings above referred to are initially applied to push jacks 193, Figure 8, and by them to needle jacks 28 which in turn control the operative positions of needles 23 in relation to the stitch cams 34, 35. Said selections are applied to needle jacks 28 when the latter are aligned in neutral or idle position which is normally effected in knitting by co-operative movement of stitch cams 34 and 35 and positioning cams 34a and 35a, Fig. 2. To effect jacquard or other pattern changes involving said determinative needle positionings, said push jacks 193 are assembled in a special change position, Figure 30, by operation of a depressor or retractor bar 194, where they are in uniform aligned relation. At this point they are in position to be selectively reconditioned or repositioned in relation to push-in bar 195 as required, and so that, when said push-in bar is next moved inwardly, any given jack will—Figure 7, (A) have its short nib 197 engaging said push-in bar 195, which produces links-links operation; or (B) have its long nib 198 engaging said push-in bar, which produces straight knitting; or (C) have neither nib engaged by said push-in bar, which idles the corresponding needle. Retractor bar 194 and push-in bar 195 are both mounted on angle bar 196 and are therefore reciprocated therewith to and from change position together.

Among the possibilities resulting from selective repositioning of said push jacks 193 as aligned in change position are: (a) all or less to links-links, Figures 24 and 29; (b) all or less to straight knitting, Figure 28; (c) some to links-links and some to straight and/or some inactive, Figure 32; (d), some simultaneously at different portions for stitch transfer in desking; (e) some simultaneously at opposite edges for narrowing; (f) some simultaneously at opposite edges for widening; (g) some at one edge for narrowing in gusset forming; (h) some or all beginning at one edge in one course and beginning at the opposite edge in the next course for widening in gusset forming; and/or (i) combinations of some of the above which will suggest themselves to those skilled in flat bed and links knitting.

In effecting said angular repositioning of push jacks 193 at the change position, the outer ends of predetermined ones thereof (1) may remain as aligned, i. e. in down (idle) position, or so that no nib will be in position to be engaged by push-in bar 195, Figures 31 and 32; (2) may be moved or tilted to "up" position (links-links), or so that the low nib 197 will be in position to be engaged by push-in bar 195, Figures 24 and 29; or (3) may be moved or tilted to middle position (straight), or so that the high nib 198 will be in position to be engaged by push-in bar 195, Figure 28.

Said push jacks 193 are then returned to their respective dwell or neutral positions in relation to push-in bar 195 where they are releasably held in one or more subsequent courses by a locking bar 285 and other devices to be described or until the next pattern change operation. At this phase each of said push jacks 193 occupies one of the three relative positions shown in Figures 6 and 7 and identified as A, links-links; B, straight knitting; and C, idle.

Said movements of push jacks 193 while in change position and when returning to their respective dwell positions for the purposes indicated are effected in part by a series of control jacks

and various devices by which the later are selectively actuated and in part by said push-in bar 185.

Adjacent to the front needle bed 25, is a control jack and bar carrying and guiding assembly, Figures 10, 11, 12, extending along the front of the machine and including devices for retaining, guiding and actuating various jack members, bars, and other elements which are operatively connected with and adjustingly actuate the push jacks 193 and thereby determine the next needle positioning movement of the corresponding needle jacks 28 and needles mounted in the several needle slots of front bed 25.

Locking bar

Said assembly, as shown, includes a longitudinally arranged comb plate 283 having vertical slots 283a, Figure 11, cut in its front face to provide in effect a jack guiding and retaining comb co-extensive with the front needle bed. Said plate has a lower and relatively wide channel 284, Figures 5, 10 and 11, extending longitudinally across said front face and intersecting the vertical slots therein. Said channel 284 accommodates a horizontally disposed vertically adjustable locking bar 285 which when in "up" position, as seen in Figure 10, operates to retain certain of the pattern control jacks, as the connecting jacks 294, in their "up" or push jack locking position during knitting; and when moved thence into "down" position, Figure 30 releases and returns said jacks and others to aligned relation. The locking bar is then raised to bring said aligned jacks into an intermediate position, Figure 31, in preparation for the next selective or change operation, as hereinafter described.

An upper and relatively narrow channel 286 extending longitudinally across the front face of said plate 283 and intersecting the vertical slots 283a therein is provided to receive and support inner end portions of cross jacks 291 as herein-after described. Upper end portions of said slots 283a are aligned with and open opposite the outer ends of corresponding needle slots in the front needle bed and receive and laterally support intermediate portions of the push jacks 193 whose inner end portions ride in said needle slots and cooperate with the needle jacks 28 therein.

As an aid to assembly of the parts as shown in Figure 10, plate 283 is provided with opposed upper and lower longitudinal V-shaped retaining grooves, of which upper groove 287 is in the upper wall of lower channel 284, and lower groove 288 is in the lower wall of said channel. These grooves receive edge portions of a composite jack and bar housing or supporting member including an upper bracket portion 289 having a V-shaped upper edge, and a lower co-operating portion 290, having a V-shaped lower edge, said upper and lower portions being coextensive longitudinally with the front needle bed 25 and comb plate 283 and having said V-shaped edges engaged with the V-shaped grooves 287 and 288 respectively of said comb plate.

As shown in Figure 10, said upper bracket portion 289 of said composite housing supports an outer upright wall which provides a stop 292 for determining the limit of outward movement of push jacks 193 and their jacquard change position. Other portions of said assembly including the comb plate 283 serve to guide, support and limit the movement of other jacks interposed between each push jack 193 and the profile bars

277, Figure 9, and/or other jack controlling and actuating devices to be described.

Pattern control jacks

5 In the embodiment of needle jack control mechanism shown in the drawings, each front bed needle jack 28 renders its corresponding needle active or inactive in response to the movements 10 of a group of jacks comprising, for each needle, the push jack 193 with its inner end or needle jack engaging portion disposed in a front needle bed groove or slot 24 and other portions in the upper end of a comb slot 283a, Figure 11, and control jacks cooperating with push jack 193 and having portions sliding in or engaging various 15 portions of said comb slot 283a. Such a group, shown in Figure 10, and some thereof individually in Figures 25, 26 and 27, respectively, includes jacks conveniently identified as main jack 293, connecting jack 294, interposed jack 295, and cross jack 291.

Main jack

Main jack 293 is a thin metal plate of irregular 25 contour. Its upper end portion or head, Figure 25, includes an upward extension 297 and an outward extension 298. An upper edge portion 299 provides a supporting surface for the bottom edge of interposed jack 295, Figures 10 and 30. The inner vertical edge of the head of main jack 293 presents a surface in limited sliding contact 30 35 with an adjacent vertical edge 300 of the connecting jack 294, Figure 26. Below said vertical surface of main jack 293, the latter has a downwardly disposed shoulder 301, Figures 25 and 32, adapted to engage an upwardly disposed shoulder 302 of connecting jack 294 when the parts are in the locked or knitting positions shown in Figure 10. An inner upwardly disposed shoulder 303 on 40 main jack 293 is disposed opposite and in the path of downward movement of bottom edge portions of locking bar 285. The bottom edge 304 of the foot portion of main jack 293 lies above and across the path of movement of various jack 45 actuating or lifting devices including the outer edge of gathering bar 327, the several profile bars 277, and the lifting plates 345. An outer upwardly disposed shoulder 305 on said jack 293 is positioned to engage and be stopped by the bottom V-shaped edge of the lower portion 290 of 50 the composite jack retainer, and thus to limit the extent of upward movement of main jack 293 to the position shown in Figure 10.

Connecting jack

Connecting jack 294 is a flat metal plate of the 55 contour shown in Figure 26. The outer upwardly disposed shoulder 302 thereof, Figure 32, and its relation to main jack 293 have been referred to above. The top edge 306 serves as a vertically adjustable positioning support for the outer end of push jack 193 and engages the under edge of those portions of said jack which engage upper end portions of vertical slot 283a of comb plate 283. The downwardly disposed edge 307 of connecting jack 294 is adapted to rest on the top edge of interposed jack 295 when the parts are positioned as shown in Figures 10, 30, 31; but is clear of said top edge when the parts are in the 60 positions shown in Figure 32, i. e. for idling the corresponding needles. The bottom edge 308 of jack 294 is positioned, Figure 10, to be engaged by locking bar 285 when the parts are in locked position and to be disengaged therefrom when said bar is moved downwardly to release or unlock 65 70 75

the parts preliminary to a jacquard change, Figure 30.

Cross jack and interposed jack in fashioning

As shown in Figure 27, each cross jack 291 is a flat metal plate provided at one side with spaced laterally extending lugs 296. These are positioned to receive between them and move the flat interposed jack 295 to and from the positions shown in Figures 30 and 32. It will be apparent that, with jack 295 interposed between shoulder 307 of connecting jack 294 and upper edge portion 299 of main jack 293, as in Figure 30, said connecting jack will be and remain raised when the main jack is lifted; but will not be or remain so raised, if interposed jack is displaced as in Figure 32.

Half of the cross jacks 291 of each needle section are provided with downwardly extending cam butts 309, and the others with similar butts 310 differently located along the length of the jack. The cross jacks 291 corresponding to needles in the left half of each needle section, Figure 12, have the butts 309; whereas the other cross jacks 291 at the right half of each said needle section, Figure 12, have the cam butts 310. The cross jacks 291, at the left in each section, Figure 12, are moved endwise by a set of cams 311 and 312 engaging butts 309 thereof and which are mounted to slide horizontally in one direction for narrowing; while those at the right in said section are actuated by a set of cams 313 and 314 engaging butts 310 thereof and mounted to slide horizontally to the same extent in the opposite direction. Thus, the number of active needles employed and hence the width of the product at any course is controllably adjustable by moving said sets of cams toward and from each other.

The cross jacks 291 and interposed jacks 295 hereinabove described also operate to progressively condition one or more needles at a time, more particularly in fashioning and gusset forming. Each increment of converging movement of said cams 311 and 313, Figure 12, for example, causes outward displacement from normal or interposed position of a predetermined number of interposed jacks 295, Figure 32, as two, or other desired practicable number, at each edge of the work in each section. This produces narrowing, since it idles the end or edge needles corresponding to said displaced interposed jacks 295 independently of any contrary selection or determination imposed on the corresponding main jacks 293 by other control devices operatively related thereto.

When cams 312 and 314 of a needle section are moved divergently from each other, they move the engaged cross jacks 291 inwardly and return interposed jacks 295 to normal interposed position, Figure 31, in relation to main jacks 293 and connecting jacks 294 which thereupon respond to positioning by said main jacks 293 and permit the corresponding needles to be restored to active operation.

The offset position of cam butts 309 on some of said cross jacks 291 in each needle section in relation to cam butts 310 on others of said cross jacks 291 permits effective reduction down to a small number of active needles by setting at any stage or in narrowing by successive convergent movements of cams 311 and 313 toward each other.

As seen in Figures 10 and 12, inner end portions of cross jacks 291 extend into and are supported in upper channel 286 of comb plate 283.

Outer end portions of the under edges of said cross jacks 291 ride on the upwardly disposed surface or shoulder 315 of a portion of the bracket member 289 where they are retained in upright sliding position by an elongated cover plate 316 having transverse slots 317 forming in effect a comb opening inwardly and downwardly and in which end portions of said cross jacks 291 are slidably engaged. Cover plate 316 is mounted on bracket 289 with part of its slotted or comb portion overlying the paths of movement of the slideable cam blocks 318 carrying said cams 311 and 312, and the slideable cam blocks 319 carrying said cams 313 and 314.

The bracket 289 provides a longitudinally extending guide rib which forms with wall portions of said bracket 289 parallel channels below said cover plate 316 to receive and support said cam blocks 318 and 319, respectively, one set thereof to each needle section. The slide rod 321 moves endwise in the outer one of said channels to actuate cam blocks 318 in the several needle sections; and the slide rod 322 operates in the inner channel to actuate the cam blocks 319 in each needle section.

Suitable means for actuating said fashioning slide rods 321 and 322, as well as the slide rods 350 and 351 which selectively position the lifting plates 345 mounted thereon, include devices, as shown in Figure 3 for example operatively connected with fashioning control mechanism and/or with gusset forming control mechanism where those are embodied in the machine. One form of fashioning control mechanism includes the control link 802, Figures 2 and 37; and said gusset forming control includes the link 808, Figure 36.

As seen in Figure 11, the comb plate 283 is provided with oblique guide slots 323. Blocks 324 are secured in spaced relation on locking bar 285, as by screws 325, and slide lengthwise, in said guide slots 323 where they are retained by plates 326 of which edge portions overlap adjacent edge portions of said slots at the inner side of comb plate 283. The desired up and down adjustment of said locking bar 285 is the vertical component of oblique sliding movement of said blocks 324 and is effected by suitable means to be described.

50

Operation of locking bar

Locking bar 285 is actuated at appropriate times in relation to operation of the aforesaid control jacks and other change devices from jacquard shaft 243 through a closed cam 334 thereon, Figures 14, 17, 18, and 20, and a crank arm 335 journaled in a bearing 336 of the frame and carrying at one end a cam roller 337 which engages the track of said closed cam 334, the other end of said crank arm 335 being pivotally connected to one end portion of said bar 285. When said crank arm 335 is rocked in one direction (clockwise Figure 14) by operation of cam 334 on shaft 243, bar 285 is moved obliquely to the right, Figure 11, from normal locking position A, Figure 18, and downwardly away from the bottom edges 308 of connecting jacks 294 to bear downwardly on the shoulders 303 of main jacks 293, thereby forcing the latter to "down" or B position, Figure 18 and Figure 30.

When crank arm 335 is rocked in the opposite direction (counterclockwise Figure 14), bar 285 is moved obliquely to the left and upwardly, Figure 11, toward said bottom edges 308 of connecting jacks 294, first, to the intermediate or

change position, C, Figure 18 and then back to normal knitting or A position, Figure 18, and against said bottom edges of the connecting jacks raising those not previously lifted. In this position of said bar 285 all the connecting jacks are locked until released for the next jacquard change.

The cam surfaces of closed cam 334 which actuate cam roller 337 include three relatively offset portions, namely, 338, 339 and 340, Figure 17, producing said A, B and C positions respectively, Figure 18, of said locking bar 285. When cam 334 is rotated with jacquard shaft 243 for pattern change purposes, these portions determine, in the sequence indicated, said three positions of locking bar 285 which are respectively the "up," or jack locking position, as during knitting, Figure 10, the "down," or jack releasing position, Figure 30, solid line, and the "middle," or jack selecting or change position, Figure 31. In a typical cycle, Figure 18, locking bar 285 drops from "up" (A) to "down" (B) position; moves up to middle (C) position where it rests momentarily while the jack selecting devices are actuated; and then returns to "up" (A) or locking position at or about the time the push-in bar 195 reaches the full line position, Figure 10, or dwell, Figure 18. The timing is such that, as push-in bar 195 moves toward said dwell position, it engages and advances any push jacks 193 whose high nibs 198 or low nibs 197 have been raised into the path of said push-in bar 195 by the preceding conditioning or change operation. Those push jacks 193 which have not been so conditioned are lifted by the said last "up" movement of locking bar 285 but reach "up" position only after push-in bar 195 has moved out of change position and are therefore not advanced by said bar into either of the two active positions.

After said return of locking bar 285 to operative locking position and during knitting, said push-in bar 195 operates in each course to actuate the selected active push jacks 193 and thus to advance the needle jacks thereby engaged. The effective position of each needle jack so advanced is determined by whether the previous operation of the push jack positioning devices at change position shall have brought the short nib 197 of push jacks 193, as in Figure 24, or the long nib 198, as in Figure 28, into position to be engaged by said push-in bar 195.

For any given course or succession of courses of knitting, and after the locking bar has been raised to "up" or locking position, some of the push jacks 193 may remain unengaged by push-in bar 195, C, Figure 7; some may be engaged by said bar through their long nibs 198, B, Figure 7; and others through their short nibs 197, A, Figure 7, depending on the pattern requirements. Also, any needle controlled by a push jack 193 having its long nib 198 engaged by push-in bar 195 operates to knit in the same bed (straight) in which it is positioned when the pattern change takes place. Where, however, the short nib 197 of a push jack 193 is engaged by push-in bar 195, the corresponding needle in one bed is caused to work for the next course in the opposite bed and thereafter, until further selection is made, alternately from one needle bed to the other (links-links) during knitting.

Profile bars

Selecting devices according to my invention also include jack lifting means in the form of pattern or profile bars, as 277, Figures 5, 9, 10, 14

and 24-32 inclusive, suitable means for selecting and actuating the same, and means for transmitting the resulting selective effect to the push jacks 193 and thence to the needle jacks.

A typical profile bar, as shown in Figure 9, has extensions 278 at its ends which, when the bars are operatively assembled, rest on brackets 279 which provide vertical guide slots for said ends and are supported in the angle bar housing 282 extending across front portions of the machine, Figures 11, 13 and 14, and forming in effect a magazine. Other bars having top edges presenting different pattern contours, if required, are removably supported on the same or like brackets and parallel with the first mentioned bar to form a set of as many bars as may be needed for the contemplated pattern changes in the fabric being produced. The brackets 279 are removable and/or adjustable to different spaced relations to accommodate profile and other bars of different lengths, and/or other bars for a different purpose.

The irregular top edge or profile of a typical profile bar 277, Figure 9, presents surfaces, as 277a, 277b, at different elevations for engaging the bottom edge of and lifting the main jacks 293 previously described. The lengths, numbers and relative longitudinal positions of said several surfaces, which may be widely varied, determine for certain purposes the numbers and relative positions of the needle jacks affected by the movement of said control jacks; and the relative elevation of each such surface determines whether or not the needle jacks controlled thereby become active, and if so, whether for links-links or for straight knitting. Thus, each profile bar 277 in a set is equipped to introduce one or more distinctive pattern features into the fabric at any desired course or courses of the several products in process of knitting.

Each profile bar 277 also has a set of two or more equi-spaced lugs 280 extending downwardly from its bottom edge. Said sets of lugs 280 are arranged on their several profile bars at different distances from the ends thereof. A plurality of sets of lifters 281 is supported on a slidable selector bar 502 and movable longitudinally therewith as a group in relation to said sets of lugs 280 to various operative lifting positions. Each of such positions is co-related with the set of lugs 280 of a particular one of said profile bars by the differential positioning of said lugs 280 along the length of said different respective bars 277.

Suitable means are provided for moving or sliding said selector bar 502 endwise to and from different positions to bring lifters 281 into engagement with one or another of said sets of lugs 280, or to neutral, or into engagement with one or another of the lugs of plate lifter bars 341 to be described. For automatic operation, a preferred embodiment of means for controllably sliding said bar 502, including chain 511 and link 807, is shown in part in Figures 2, 3 and 35.

Means for lifting said selector bar 502 at its various positions of adjustment in relation to said lugs 280 and thus to lift selected ones of said profile bars 277 through said lifters 281, Figures 5 and 30 to 32, will be described later along with means for lifting the gathering bar 327.

Each end of said housing 282 is secured to a plate 661, Figure 14, mounted to slide in slots 662 provided in the frame. Thus, said housing and the parts carried thereby may be withdrawn outwardly by hand from their operative position as shown in Figure 10, for any desired or necessary

purpose, for example, to replace one or more of the profile bars 277 with another or others thereof.

Gathering bar

Devices other than the profile bars 277 for engaging and lifting the main jacks 293 include an elongated angle plate, Figures 10, 11 and 14, extending across the length of the front needle bed and having a horizontal outwardly extending flange, conveniently identified as a "gathering" bar 327. The outer edge portion thereof extends under the bottom ends of all the main jacks 293 in such a manner that, when said gathering bar 327 is raised, all of said jacks 293 are lifted a corresponding extent. Thus, the gathering bar is conveniently employed where the pattern requires a change to some arrangement whereby all the active needles operate alike either for links-links or for straight knitting.

As shown in Figures 10, 14 and 16, a left end portion of gathering bar 327 is pivotally mounted on one arm 328 of a rocking lever pivotally supported in a bearing at 332 and having its other arm 329 pivotally connected to a spring biased push rod 330 at 331, Figure 14. Similar suspensions are provided at suitably spaced positions along the length of gathering bar 327. When the lever arms 328 are tilted upwardly from normal inoperative position, as by thrusting said push rod 330 to the right, Figure 14, against tension of spring 330a which normally biases said push rod 330 toward the left, gathering bar 327 is raised part way from its inactive or down position to lift all the main jacks 293 to an intermediate (straight) position, Figure 28. When said gathering bar 327 is raised the whole distance to its up position, Figure 24, all said jacks 293 are raised to their top or links-links position. These movements of main jacks 293 effect corresponding repositionings of push jacks 193, except where interposed jacks 295 are in the "out" position, Figure 32.

Actuating the gathering bar and the profile bars

Said spring biased push rod 330 for lifting gathering bar 327 has at its left end, Figure 16, an adjusting bolt 333 by which to more accurately adjust the operating relation of said push rod to adjacent selective rod actuating devices, better shown in Figures 14 and 15, and which have operative connection with jacquard shaft 243, Figure 23. Said devices for actuating push rod 330 are in part the same as those employed in actuating a push rod 509, Figure 16, which, with connected parts, operates to lift the selector bar 502 and hence the profile bar lifters 281 and thereby the profile bars 277, previously described, and/or the adjustable lifting plates 345, hereinafter described.

As shown in Figures 14 and 15, the free end of adjusting bolt 333 on gathering bar lifting push rod 330 lies opposite and, in operation, is engaged by one of three end face portions of an arm 627 of a combined rod pusher pivotally connected to the upper end of a rocking lever 639 at 639a. The other arm 628 thereof is parallel with said arm 627 and spaced therefrom by a weight 629 secured between them, Figure 16. Said arm 628 which actuates profile bar lifting push rod 509 is also provided with two end face portions arranged to cooperate with the end of an adjusting bolt 638 on the end of said rod 509.

A roller 630 journaled at one side of and near the free end of said arm 628 is positioned to bear

on the upper surface of an extension 631 at the outer end of a lever 632 pivoted at 633, Figures 5, 16 and 23. The free end of said combined rod pusher which includes said arms 627 and 628 is angularly adjustable in a vertical direction on pivot 639a to present said different face portions of the ends of arm 627 for engagement with said bolt 333 to actuate gathering bar lifting push rod 330; or to present said different face portions of the end of arm 628 for engagement with said bolt 638 to actuate said profile bar lifting push rod 509, or under some conditions to simultaneously present a portion of arm 627 and a portion of arm 628 for engagement with said bolts 333 and 638 respectively.

Said adjusting or vertical angular movement of the ends of arms 627 and 628 is effected by any suitable means, such for example as the devices shown in Figures 5, 16 and 23, by which said arms are operatively connected to jacquard control shaft 256. For said purposes, a link 634 connects the other (inner) end of said lever 632 with an arm 635 secured on said control shaft 256, which, as seen in Figure 22, also carries the detent arm 255 movable by rotation of said control shaft 256 in either direction to and from the inactive or full line position there shown to control operation of said jacquard operating shaft 243.

In the full line position of detent arm 255, as shown, jacquard shaft 243 is at rest; and lever 632, Figures 5 and 23, occupies its intermediate or inoperative position, whereby said combined rod pusher is disposed in its middle or neutral angular position, as shown in Figure 14. When said shaft 256 is rotated in one direction from neutral, said arm 635 thereon is displaced to bring push arm 627 into position to actuate push rod 330 and thus to lift gathering bar 285 into one or another of its operative positions. When said shaft 256 is rotated in the opposite direction from neutral, arm 635 is displaced to bring push arm 628 into position to actuate push bar 509 and thus to lift a profile bar into its operative jack lifting position, and/or a fashioning bar 341 into one or another of its operative positions.

As shown more clearly in Figure 15, the free end of arm 628 has the face portions 628a and 628b, which operate rod 509 to effect the lift imparted to the selector bar 502 and hence to profile bars 277. Arm 627 has the face portions 627a, 627b, at one side of a zero position, and 627c at the other side thereof, respectively, which operating through rod 330 determine the extent of lift imparted to the gathering bar 327. Said faces are arranged in two stages of lateral projection, 628a, 628b and 627a being more extended, and 627b and 627c being less extended.

With the bolts 333 and 628 on the ends of rods 330 and 509, respectively, adjusted as shown in Figure 16, one or the other or both of said rods will be displaced from the idle position shown by endwise thrusts of said arms 627 and 628 toward the right, depending on which of said face portions thereof are thereby brought against the ends of said bolts. The illustrated embodiment provides for angular movement of said arms 627 and 628 to bring said end faces thereof into any of four different operative positions of vertical adjustment in relation to the ends of said rods 330 and 509, two positions above and two below the zero or neutral position shown in Figure 14 at which no endwise thrust is imparted to said arms 627 and 628.

The gathering bar 327 is movable to two different elevations, the lower one for straight

knitting, Figure 28, and the higher for links-links operation, Figure 24. Accordingly, the free ends of arms 627 and 628 are adjusted upwardly to bring the face portion 627b of arm 627, Figure 15, into line with the end of push rod 330 for straight knitting; or to bring the face portion 627c into said position for links-links. In both of these positions of arm 627, the free end of arm 628 is out of operative position; and, therefore, no thrust is imparted to the profile bar actuating rod 509.

The profile bar lifting and selecting bar 502 is lifted only one step in actuating said profile bars 277 or the lifting plates 345, hereinafter described. The elevations of the several top edges of each profile bar 277 determine their effect on the pattern in terms of straight or links-links knitting, or idling.

If the free ends of arms 627 and 628 are adjusted downwardly to bring the face portion 628a opposite the end of profile bar actuating push rod 509, selecting bar 502 is lifted and the profile bars 277 control the pattern without modification from the gathering bar.

If, however, said downward adjustment of the free ends of arms 627 and 628 is of less extent than that last described and brings the face portion 628b opposite the end of said rod 509, it also brings the face 627c opposite the end of gathering bar push rod 330; and both said rods are actuated when arms 627 and 628 are thrust to the right, Figure 14. The effect on the pattern is to produce straight knitting on all needles except such as might be made links-links by profile characteristics, if any, of one of the profile bars 277 or the lifting plates 345 lifted simultaneously with the gathering bar 327.

To produce the effect first above noted on gathering bar 327, control shaft 256 is actuated to swing arm 635, Figure 5, downward through a predetermined short arc. Lever 632 is thereby tilted and raises the free ends of arms 627 and 628 to the position wherein the face portion 627b comes opposite bolt 333 on gathering bar lifting push rod 330. When said arm 629 is moved endwise toward the right, Figure 14, rod 330 is moved a short or part distance against resistance of spring 330a as described; and rod 509 is not moved. In the second raised position of arm 627, rod 330 is moved the full distance by face 627a; and rod 509 is not moved.

Profile bar push rod 509 is actuated when arm 635 on control shaft 256 is deflected upwardly, Figure 5, to bring one or the other of the face portions 628a or 628b of arm 628 down into first or second lowered position of said arm, in relation to adjusting bolt 638 on profile bar push rod 509, under the circumstances above described.

The endwise or thrust movements to the right of arms 627 and 628, respectively, above referred to are effected by the rocking lever 639, Figure 14, pivoted at 640. The lower arm of said lever 639 carries a cam roller 641, Figure 23, and is biased by a spring 642, Figure 14, in a direction to engage said roller with a cam 643 on a cam disc 644 fixed to jacquard shaft 243.

Thus, when said shaft 243 is rotated to effect a jacquard change by operation of devices for that purpose, as shown in part in Figures 14 to 23 inclusive, cam 643 engages cam roller 641 which rocks arm 639 to impart endwise reciprocating movement to the push member comprising the previously described parallel pivoted arms 627 and 628. This actuates one or the other of rods 330 and 509, depending on whether opera-

tion of the pattern control devices, at that stage, has deflected the free ends of said arms upwardly or downwardly from the neutral position shown in Figure 14, except that both rods 330 and 509 are actuated, as previously described, when said free ends are in one of their two down positions. The direction and extent of these movements is determined by control devices including the links 688, 688-a, Figures 2, 33 and 34. The timing of said movements in relation to the cycle of cycle of push-in bar 195 is shown in Figure 19.

Jack selection for decking

Means for lifting predetermined ones of main jacks 293, more particularly to condition the corresponding needles for casting off in the decking operation which accompanies each narrowing and for another purpose to be described, includes jack lifting or fashioning plates, 345, 346, means for moving said plates to and from different operative positions in relation to main jacks 293, and means for lifting said plates while in said operative positions to one or another raised position.

An intermediate element for raising the jack lifting plates 345, 346, in each knitting section is the fashioning bar 341, Figure 11, arranged at one side of and parallel with the profile bars 277, Figure 13, and having end extensions 342 which rest on the spaced shoulder brackets 279. Extending downwardly from the bottom surface of the fashioning bar 341 are spaced short lugs 343, which are actuated when it is desired to condition edge needles for casting off stitches in narrowing, said lugs being shown as insertable and removable split pins mounted in downwardly opening recesses, Figure 10.

Similarly mounted and spaced long lugs 344, offset from short lugs 343, are provided for fashioning bar 341 and actuated when it is desired to bring edge needles from the rear to the front bed, or to make a fashioned product having a links-links edge.

The lifters 281 on selector bar 502 are movable therewith on endwise adjustment of said selector bar into positions to engage either said short lugs 343 or said long lugs 344. Thus, when selector bar 502 is in one of these positions and is lifted by operation of push bar 509, said lifters 281 raise plate lifter bar 341 upwardly from its "down" position to its middle position, if engaging said short lugs 343, and to its "up" position, if engaging said long lugs 344, with different operative effects hereinafter described and which are produced through the resulting operation of lifting plates 345, 346 controllably adjustable in relation to the main jacks 293 and to each other.

The jack lifting or fashioning plates

The above described raising of plate lifter bar 341 is transmitted in each knitting section to a set of longitudinally adjustable spaced jack lifting plates 345 and 346 respectively, Figures 10, 11, 12 and 13, which are mounted to slide vertically in undercut V-slots 347 provided in carriers or blocks 348 and 349, Figure 12. To adjust the spacing between said plates 345 and 346, i. e. to move said plates toward and from each other, and thus to determine which main jacks 293 and consequently which end needles are to be effected by lifting movement thereof, said blocks 348 and 349 are slideable toward and from each other in each knitting section. For this purpose block 348 is secured to a portion of the upper slide rod 350; and block 349 to a portion

of the lower slide rod 351. Endwise motion is imparted simultaneously to both of said slide rods 350 and 351, but in opposite directions, by suitable means shown in part in Figure 3 and which simultaneously actuate the previously described fashioning slide rods 321 and 322. Said blocks 348 and 349 are thereby actuated to slide horizontally in an undercut channelled longitudinally extending guide way 352, Figure 10. The direction and extent of this movement is determined by endwise movement of said slide rods 350 and 351 effected in response to control devices including the control link 662, Figures 2 and 37, which also control the corresponding widening and narrowing endwise movements of said slide rods 321 and 322, respectively, in actuating the fashioning cams 311, 312, 313 and 314.

As shown in Figure 10, each lifting plate, as 345, includes a lower flange and an upper flange offset therefrom and connected thereto by a shoulder 353 which rests on an upper surface portion of fashioning bar 341, or in position to be raised and lowered when and to the extent that said bar 341 is raised and lowered. The top edge of said upper flange is long enough to underlie portions of the bottom edges 304 of one or more of said main jacks 293, for example five, as shown, Figure 11.

Since different pattern characteristics in knitting may require the lifting of more or fewer of the main jacks 293 for conditioning more or fewer needles at the opposite lateral edges of the work, as in connection with decking for narrowing or for the other purposes stated, lift plates 345, 346, with upper flanges having different appropriate widths of top lifting surface or edge for affecting different numbers of needles within appropriate limits under the particular circumstances of each case may be interchangeably mounted in said vertical slots 347 of blocks 348 and 349. The extent of positioning movements of slide rods 321 and 322 is also varied to accommodate narrowing by different numbers of needles at each edge of the work.

A set of said lift plate carriers or blocks 348 and 349 is provided for each needle section; and the sets of said blocks for all needle sections are moved simultaneously by said slide rods 350 and 351. Also, each set of said blocks is effectively co-related in operation with a corresponding set of said cam blocks 318, 319. For example, the lift plate carrying block 348, Figure 13, operates with cam carrying block 318, Figure 12; and said blocks are advanced and retracted in proper synchronized relation. Accordingly, in decking for narrowing, if the pattern requires decrease of two needles, for example, at each edge of the work, the top edges of the lifting plates, as 345, 346, will be of sufficient width to lift at least that many jacks and hence to advance at least that many needles from which to remove the stitch loops as a preliminary to idling of said two needles in the next course. The several mechanisms hereinafter described for simultaneously moving said lift plate carrying blocks 348 and 349 toward and from each other and for simultaneously moving said cam blocks 318 and 319 toward and from each other are operatively connected to affect the proper needles in each narrowing and widening operation.

In selecting for decking in advance of narrowing, the effect of raising the lifting plates 345 and 346 to middle position, as when the short lugs 343 of the plate lifter or bar 341 are engaged by the lifters 281, Figure 31-A, is to insure that the

so selected needles at the edges of the work shall be moved inwardly into position to have the stitch loops removed from them by the decking devices which later transfer said loops to the next adjacent needles. Said selected needles are then dropped or idled in the jacquard change for the next course, thereby nullifying any needle affecting condition which might otherwise be imposed on them by an accompanying pattern change operation of the profile bars 271 or of the gathering bar 327 in relation to the main jacks 293. If narrowing continues, said lifting plates 345 and 346 and said blocks 318 and 319, respectively, are meanwhile again moved toward each other and the cycle repeated.

The lifting plates 345 and 346, may also be raised to lift one or more main jacks 293 at each end of each knitting section to links-links or extreme "up" position, Figure 31-B. In such case, selector bar 502 brings lifting lugs 281 under the long lugs 344 of lifting bar 341. When said bar 502 is then raised by endwise thrust of arm 628 through face 628a or face 628b thereof to actuate profile bar push rod 509, the needles controlled by the raised main jacks 293 will move from the rear bed to the front bed, or will operate links-links, regardless of any different mode of operation of the remaining needles.

In widening, the cam blocks 318 and 319 are moved away from each other. Hence cams 312 and 314 actuate cross jacks 291 to return interposed jacks 295 to normal position, as in Figure 10, thereby insuring that the affected edge needles will be "picked up" in the next course. If the lifting plates 345 and 346 are not actuated in said widening, the edge needles so picked up will be restored to the normal conditioning or positioning effect of profile bars 271 and/or the gathering bar 327 in relation to main jacks 293 incident to a pattern change operation. If, however, in picking up the edge needles in widening, the pattern requires links-links operation thereof, or a shift of said needles from rear to front bed, the lifting plates 345 and 346 are actuated through the long lugs 344 on fashioning bar 341 to raise selected push jacks 193 to the "up" position, shown in Figure 24.

The illustrated machine also includes devices for actuating the control jack system in a manner to form gussets. This involves a special form of narrowing wherein selected needles are idled at one end only of each course and alternately at the opposite ends of successive courses without however, casting off their loops. Narrowing is followed by a single widening step or return at each edge to normal or unnnarrowed width to produce graduated fullness or a gusset in a portion of the knitted fabric, as for example, in the shoulder or nape portion of a sweater, or in other garments or products.

Actuating the needle selecting devices

As previously noted, the fashioning cams 311 and 312, Figure 12, are actuated by slide rod 321; and fashioning cams 313 and 314, by slide rod 322. The lifting plates 345 and 346 employed in decking are also moved toward and from each other for selective positioning in cooperation with the above mentioned fashioning cams by slide rods 350 and 351 respectively.

Said slide rods 321 and 322, and 350 and 351 may be actuated and controlled by any suitable means. For automatic operation in connection with the machine illustrated wherein the fashioning cams 311, 312, 313, 314 are subject to dual

control, i. e., for fashioning and for gusset forming, said means include the devices shown in Figures 2, 3 and 4. As there shown, outer end portions of said slide rods 321 and 351 are operatively connected to a sliding nut 356, which, for the purpose of actuating said rod 351, has a depending arm 351, Figure 4, supporting the outer end portion of said rod. Outer end portions of rods 322 and 350 respectively are operatively connected to a sliding nut 358. Wall portions of a longitudinally extending housing assembly 359 provide guiding and supporting interior surfaces for said sliding nuts 356 and 358. These are actuated to move back and forth endwise for fashioning by rotatable and slidable worm shafts 360 and 361, respectively, having threaded portions on which said nuts are engaged.

The outer end wall portion of housing 359 provides bearings, Figure 2, for smooth end portions of said worm shafts 360 and 361, also for the hub of a sprocket 364 which is splined on said shaft 361. A pinion 365 is keyed on the hub of sprocket 364 and meshes with a pinion 366 having hub portions journaled in said outer end portion of housing 359, said pinion 366 being splined at the end of worm shaft 360. Thus, when sprocket 364 is rotated by any suitable means, its worm shaft 361 rotates a corresponding extent in one direction; and the other worm shaft 360 rotates the same amount and at the same rate in the opposite direction. This rotation of said worm shafts 360 and 361 moves the nut 356 and the rods 321 and 350 and the nut 358 and the rods 322 and 351 thereto attached simultaneously in opposite directions. A preferred mechanism for controllably rotating said worm shafts to effect the resulting widening or narrowing in fashioning is indicated in part in Figures 2 and 37 and includes link 802.

For gusset forming, said slide rods 321 and 322 and 350 and 351 are actuated by sliding said worm shafts 360 and 361 endwise and thus producing the required endwise movement of the sliding nuts 356 and 358 to which said slide rods are secured. A preferred mechanism including a link 803 for controllably sliding said worm shafts endwise is indicated in part in Figures 2 and 36.

The above described needle selection and control devices embodying my invention provide a relatively simple compact and rugged mechanism having features which adapt it particularly to high speed production on automatic machines, as where the stitch cams run up to fifty or more courses per minute.

Said devices also present advantages in multiple operation, as where a plurality of garments, or parts, are simultaneously knitted on the same machine; and the pattern of all is determined by a common pattern control mechanism.

My improved needle selection and control devices as described have great flexibility in use and are capable of being operated under automatic or other control to produce in minimum time the widest variety of textures and other pattern characteristics, some of which cannot be produced commercially on conventional power knitting machines.

The above described mechanisms are also shown and described but not independently claimed in my co-pending application Serial No. 530,761 filed herewith and of which the present application is in effect a division.

I claim:

1. In needle jack selecting and positioning mechanism for knitting machines, the combina-

tion of a plurality of push jacks, a plurality of connecting jacks each arranged to engage a portion of one of said push jacks, means for moving said connecting jacks in one direction to effect angular adjustment of the push jacks, said means including a portion arranged and adapted to move some of said connecting jacks in said direction differentially in relation to other of said connecting jacks, and means for moving said connecting jacks in the opposite direction.

5 2. In needle jack selecting and positioning mechanism for knitting machines, the combination of a push jack, a connecting jack arranged to engage a portion of said push jack, means for moving said connecting jack in one direction to effect angular adjustment of the push jack, said means including a main jack operatively related to said connecting jack, a profile bar having different portions of one edge exposed at different 15 distances from an end edge portion of said main jack, and means for moving said profile bar in a direction to actuate said main jack.

20 3. In needle jack selecting and positioning mechanism for knitting machines, the combination of a push jack, a connecting jack arranged to engage a portion of said push jack, means for moving said connecting jack in one direction to effect angular adjustment of the push jack, said means including a main jack operatively related to said connecting jack, a lifting plate adjustable 25 to and from a position wherein a portion thereof is operatively related to a portion of said main jack, and means for moving said lifting plate in a direction to engage and actuate said main jack.

30 4. In needle jack selecting and positioning mechanism for knitting machines, the combination of a push jack, a connecting jack arranged to engage a portion of said push jack, means for moving said connecting jack in one direction to effect angular adjustment of the push jack and means including a main jack operatively related to said connecting jack, a gathering bar normally spaced from said main jack and movable into position to engage and actuate said main jack, 35 and means for moving said gathering bar different distances from normal position to engage and impart to said main jack movements of different extent.

40 5. In needle jack selecting and positioning mechanism for knitting machines, the combination of a push jack, a connecting jack arranged to engage a portion of said push jack, means for moving said connecting jack in one direction to effect angular adjustment of the push jack, said 45 means including a locking bar operatively related to said connecting jack, and means for moving said locking bar by a plurality of steps in said one direction and by a single step in the opposite direction.

50 6. In needle jack selecting and positioning mechanism for knitting machines, the combination of a push jack, a connecting jack arranged to engage a portion of said push jack, means for moving said connecting jack in one direction to effect angular adjustment of the push jack, said 55 means including a main jack operatively engaging said connecting jack, a locking bar operatively related to said connecting jack, and means for moving said locking bar in one direction to engage and move said connecting jack in said direction and, in the opposite direction, to engage and actuate said main jack and thereby to move said connecting jack in said opposite direction.

60 7. In needle jack selecting and positioning mechanism for knitting machines, the combina-

tion of a push jack, a connecting jack arranged to engage a portion of said push jack, means for moving said connecting jack in one direction to effect angular adjustment of the push jack, said means including a main jack operatively related to said connecting jack, a plurality of profile bars each having different portions of one edge exposed at different distances from an end edge portion of said main jack, and means effective at different positions on said several profile bars to engage and move one thereof in a direction to actuate said main jack while the others remain unmoved.

8. In needle jack selecting and positioning mechanism for knitting machines, the combination of a push jack, a connecting jack operatively engaging a portion of said push jack, a main jack, an interposed jack movable to and from a position where it engages both said main and said connecting jack and transmits movement from said main jack to said connecting jack, means for moving said main jack in a direction to actuate said connecting jack through said interposed jack, and means for moving said interposed jack from and to said movement transmitting position.

9. In needle jack selecting and positioning mechanism for knitting machines, the combination of a plurality of connecting jacks, a main jack operatively engaging each connecting jack, an interposed jack normally positioned to transmit movement from each said main jack to each said connecting jack, a cross jack operatively engaging each interposed jack and arranged and adapted to move the latter from and to said normal position, a set of spaced lifter plates movable toward and from each other and each arranged and adapted to engage and actuate a main jack, a set of cams arranged and adapted to engage said cross jacks and movable toward each other to actuate said cross jacks in one direction and from each other to actuate said cross jacks in the opposite direction, and means operatively connected to said lifter plates and to said cams to move said lifter plates toward and from each other and simultaneously therewith to move said cams toward and from each other.

10. In needle jack selecting and positioning mechanism for knitting machines, the combination of a connecting jack having a projecting shoulder, a main jack having a projecting shoulder positioned to be engaged by said shoulder of the connecting jack, a locking bar movable in one direction to engage said connecting jack and to move said shoulder thereof into engagement with said shoulder of the main jack and movable in the opposite direction to engage said main jack and to move said shoulder thereof into engagement with said shoulder of the connecting jack, and means for actuating said locking bar.

11. In needle jack selecting and positioning mechanism for knitting machines, the combination of a connecting jack having a projecting shoulder, a main jack having a projecting shoulder positioned to be engaged by said shoulder of the connecting jack, a locking bar movable in one direction to engage said connecting jack and to move said shoulder thereof into engagement with said shoulder of the main jack and movable in the opposite direction to engage said main jack and to move said shoulder thereof into engagement with said shoulder of the connecting jack, and cam means operatively connected with said locking bar and arranged and adapted to move said bar in said opposite directions.

12. In needle jack selecting and positioning mechanism for knitting machines, the combination of a plurality of main jacks each movable from inactive to one of different active operative positions, a gathering bar movable into and out of actuating engagement with all of said main jacks, other main jack actuating devices movable into and out of actuating engagement with less than all of said main jacks, an actuating rod operatively connected to said gathering bar, an actuating rod operatively connected to said other main jack actuating devices, and means for effecting operative movement of said actuating rods.

13. In needle jack selecting and positioning mechanism for knitting machines, the combination of a plurality of main jacks each movable from inactive to one of different active operative positions, a gathering bar movable into and out of actuating engagement with all of said main jacks, other main jack actuating devices movable into and out of actuating engagement with less than all of said main jacks, an actuating rod operatively connected to said gathering bar, an actuating rod operatively connected to said other main jack actuating devices, an adjustably mounted rod actuating member having different rod engaging portions movable into and out of operative position opposite end portions of said rods, means for varying the position of said member to bring said rod engaging portions into and out of said operative positions in relation to said end portions of the rods, and means for effecting rod actuating movement of said rod actuating member.

14. In a needle jack selecting and positioning mechanism for knitting machines, the combination of a plurality of cross jacks mounted to slide endwise and each jack having a cam butt, a set of cams arranged to engage the butts of some of said cross jacks, another set of cams arranged to engage the butts of others of said cross jacks, means for moving said sets of cams toward each other to slide the thereby engaged cross jacks in one direction and away from each other to slide said cross jacks in the opposite directions.

15. In a needle jack selecting and positioning mechanism for knitting machines, the combination of a plurality of cross jacks mounted to slide endwise and each jack having a cam butt, a set of cams arranged to engage the butts of some of said cross jacks, another set of cams arranged to engage the butts of others of said cross jacks, means for moving said sets of cams simultaneously toward each other and simultaneously away from each other.

16. In a needle jack selecting and positioning mechanism for knitting machines, the combination of a plurality of cross jacks mounted to slide endwise and each jack having a cam butt, a set of cams arranged to move in one path to engage the butts of some of said cross jacks, another set of cams arranged to move in another path parallel with said first mentioned path to engage the butts of others of said cross jacks, and means for moving said sets of cams simultaneously toward each other and simultaneously away from each other.

17. In a knitting machine having a needle bed presenting a plurality of needle sections and stitch cam means, thread carrying means, and brushes cooperating with the needles in each section and connected to operate simultaneously in all sections, the combination of a connecting jack operatively related to each needle, a main jack positioned to actuate each connecting jack, an inter-

60
65
70
75

endwise and each jack having a cam butt, a set of cams arranged to move in one path to engage the butts of some of said cross jacks, another set of cams arranged to move in another path parallel with said first mentioned path to engage the butts of others of said cross jacks, and means for moving said sets of cams simultaneously toward each other and simultaneously away from each other.

18. In a knitting machine having a needle bed presenting a plurality of needle sections and stitch cam means, thread carrying means, and brushes cooperating with the needles in each section and connected to operate simultaneously in all sections, the combination of a connecting jack operatively related to each needle, a main jack positioned to actuate each connecting jack, an inter-

posed jack arranged to transmit movement between said connecting jack and said main jack, when interposed between said latter jacks, a cross jack operatively engaging each interposed jack and having a cam butt, parallel cam rods mounted to slide endwise, one of said rods carrying a plurality of sets of cams one set for each said needle section and said set of cams being positioned to engage the butts of some of the cross jacks in said section, and the other of said set of cams being positioned to travel in a path parallel with that of said first set in each section and to engage the butts of others of said cross jacks in said section, and means for moving said rods endwise simultaneously, one in one direction and the other in the opposite direction.

18. In a knitting machine having a needle bed presenting a plurality of needle sections and stitch cam means, thread carrying means, and brushes cooperating with the needles in each section and connected to operate in all sections, the combination of a main jack operatively related to each needle, parallel positioning rods extending across said needle sections and mounted to slide endwise, a plurality of lifter plates mounted in spaced relation on each rod, one of the plates on each rod in each section being operatively related to some of the main jacks therein and each of said plates having a portion adapted to engage and actuate one or several of said main jacks, means for moving said positioning rods endwise simultaneously, one in one direction and the other in the opposite direction, whereby the lifting plates in each section are adjusted toward or from each other, and means for moving said plates into engagement with said main jacks at various positions of adjustment of said plates effected by said endwise movement of said positioning rods.

19. In needle jack selecting and positioning mechanism for knitting machines, the combination of a push jack, a push-in bar, means for moving said push-in bar to pattern change position, means for moving said push jack to pattern change position, and means for adjusting said push jack in relation to said push-in bar while the latter is in pattern change position.

20. In needle jack selecting and positioning mechanism for knitting machines, the combination of a push jack having a nib extending therefrom, means for moving said push jack to pattern change position, a push-in bar mounted to reciprocate in a direction lengthwise of said push jack to and from pattern change position, and means operative when said push-in bar and said push jack are in pattern change position for moving said push jack in a direction to bring said nib into the path of said push-in bar as the latter moves from pattern change position.

21. In needle jack selecting and positioning mechanism for knitting machines, the combination of a plurality of push jacks each having a nib extending therefrom, means for moving said push jacks to pattern change position, a push-in bar mounted to reciprocate in a direction lengthwise of said push jacks and movable to and from pattern change position, means operative when said push-in bar and said push jacks are in pattern change position for selectively adjusting some of said push jacks in a direction to bring said nibs thereof into the path of said push-in bar as the latter moves from pattern change position, and means for repositioning other of said push jacks and for locking said selectively adjusted push jacks in push-in bar engaging position.

22. In a needle jack selecting and positioning mechanism for knitting machines wherein the needle jacks are slidably mounted in the grooves of a needle bed, the combination of a push jack for each said needle jack, said push jack having an inner end riding in said groove in position to engage and move said needle jack and an outer end extending outwardly beyond said groove, said push jack being mounted to slide endwise to and from a pattern change position, means for moving said push jack endwise from said pattern change position, a push jack engaging and conditioning member arranged and adapted to support portions of said push jack outside of its needle bed groove, said member being adjustable toward and from the path of movement of said push jack moving means, and means for moving said adjustable push jack engaging member to and from different positions of adjustment in relation to said path of movement of the push jack moving means.

23. In needle jack selecting and positioning mechanism, the combination of a slidably mounted push jack, a depressor bar arranged and adapted to engage and move said push jack endwise from neutral position to pattern change position, a push-in bar arranged and adapted to engage and move said push jack endwise from pattern change position to neutral position, and means for effecting angular movement of said push jack while in said pattern change position to vary the operative relation thereof to said push-in bar while the latter is also at pattern change position.

24. In needle jack selecting and positioning mechanism, the combination of a slidably mounted push jack, a depressor bar arranged and adapted to engage and move said push jack endwise from neutral position to pattern change position, a push-in bar operatively connected to and reciprocatable with said depressor bar and arranged and adapted to engage and move said push jack endwise from pattern change position to neutral position, and means for effecting angular movement of said push jack while in said pattern change position to vary the operative relation thereof to said push-in bar while the latter is also at pattern change position.

25. In needle jack selecting and positioning mechanism, the combination of a slidably mounted push jack having a high nib and a low nib extending therefrom, depressor means arranged and adapted to engage and move said push jack endwise from neutral position to pattern change position, a push-in member arranged and adapted to engage one of said nibs to move said push jack from pattern change position to neutral position, and means for effecting different angular movements of said push jack while in said pattern change position to bring one or another of said nibs into the path of said push-in member to be engaged thereby as it moves from pattern change position to neutral position.

26. Apparatus for selectively conditioning needle jacks in the bed of a knitting machine whereby their respective needles will be active or be idle, said apparatus comprising a plurality of push jacks, each operatively related to one of said needle jacks and being slidably mounted for endwise movement between pattern change position and needle jack conditioning position, means for assembling said push jacks in pattern change position, means operative while said push jacks are at pattern change position to adjust selected ones of said push jacks into posi-

tion to render their respective needle jacks active, and separately operative means for adjusting the remaining push jacks into position to render their respective needle jacks idle.

27. In a knitting machine, the combination of a needle bed provided with a set of needles slidably mounted therein, means including a push jack for effecting individual conditioning movement of each of said needles, a slidable cam operatively arranged in relation to said push jacks and movable in one direction to effect narrowing by one or more end needles of said set and in the opposite direction to effect widening, means for moving said cam step by step for narrowing and widening in fashioning, means for moving said cam step by step for narrowing, and means for moving said cam in a single step for widening to vary the fullness of the product.

28. In a knitting machine, the combination of a needle bed provided with a set of needles slidably mounted therein, means including a push jack for effecting individual conditioning movement of each of said needles, a slidable cam operatively arranged in relation to said push jacks and movable in one direction to effect narrowing by one or more end needles of said set and in the opposite direction to effect widening, means for moving said cam step by step for narrowing and widening in fashioning, means for moving said cam step by step for narrowing, means for moving said cam in a single step for widening to vary the fullness of the product, means for casting loops off said end needles, and means operatively connected with said push jacks and movable in unison with said slidable cam to maintain needles adjacent to said end needles in condition to receive the loops cast off of said end needles in fashioning.

29. In a knitting machine for making fashioned products having links-links edge portions, the combination of opposed needle beds provided with a set of needles mounted to slide therein to and from idle, straight and links-links knitting positions, means including a push jack adjustable for effecting individual conditioning movement of each of said needles, and means operatively connected with said push jacks and adjustable longitudinally of one of said needle beds for conditioning active end needles of the set to move from and to the rear bed in knitting regardless of the mode of operation of the remaining active needles.

30. In a knitting machine for making fashioned products having links-links edge portions, the combination of opposed needle beds provided with a set of needles mounted to slide therein to and from idle, straight and links-links knitting positions, means including a push jack adjustable for effecting individual conditioning movement of each of said needles, a lifting plate operatively connected with said push jacks, means for moving said plate longitudinally of one of said needle beds, and means for raising said lifting plate from inactive position to different operative positions in one of which said plate actuates a push jack to effect links-links operation of its corresponding needle and in another of which said plate actuates said push jack to condition the needle as for straight knitting.

31. In a knitting machine, the combination of 70 a push jack mounted for adjusting movement toward and from different operative positions, a main jack movable toward and from said push jack, a connecting jack having a portion operatively positioned between said main jack and said

push jack and adapted to impart adjusting movement to said push jack, an interposed jack, means for moving said interposed jack into and out of operative position between said main jack and said portion of said connecting jack, whereby when said interposed jack is in said operative position said connecting jack is conditioned to impart adjusting movement from said main jack to said push jack, and means for moving said main jack.

32. In a knitting machine, the combination of a plurality of push jacks, a plurality of main jacks, a plurality of connecting jacks each having a portion operatively positioned between one of said push jacks and one of said main jacks and arranged and adapted to impart adjusting movement to said push jacks when said main jacks are moved toward said connecting jacks, and main jack actuating means for moving said main jacks toward said connecting jacks and having main jack engaging portions arranged in differentially spaced relation to different ones of said main jacks.

33. In a knitting machine, the combination of 25 a plurality of push jacks, a plurality of main jacks, a plurality of connecting jacks each having a portion operatively positioned between one of said push jacks and one of said main jacks and arranged and adapted to impart adjusting 30 movement to said push jacks when said main jacks are moved toward said connecting jacks, and main jack actuating means having main jack engaging portions for moving said main jacks toward said connecting jacks.

34. In a knitting machine, the combination of a plurality of push jacks, a plurality of main jacks, a plurality of connecting jacks each having a portion operatively positioned between one of said push jacks and one of said main jacks and arranged and adapted to impart adjusting 40 movement to said push jacks when said main jacks are moved toward said connecting jacks, and main jack actuating means having main jack engaging portions adjustable to different positions to engage and move different ones of said main jacks.

35. In a knitting machine, the combination of 45 a plurality of push jacks, a plurality of main jacks, a plurality of connecting jacks each having a portion operatively positioned between one of said push jacks and one of said main jacks and arranged and adapted to impart adjusting movement to said push jacks when said main jacks are moved toward said connecting jacks, main 50 jack actuating means having main jack engaging portions for moving said main jacks toward said connecting jacks, and means for varying the extent of movement of said main jack engaging portions and thereby the extent of movement of said main jacks.

36. In a knitting machine, the combination of 55 a plurality of push jacks, a plurality of main jacks, a plurality of connecting jacks each having a portion operatively positioned between one of said push jacks and one of said main jacks and arranged and adapted to impart adjusting movement to said push jacks when said main jacks are moved toward said connecting jacks, main 60 jack actuating means having main jack engaging portions adjustable to different positions to engage and move different ones of said main jacks, and means for varying the extent of movement of said adjustable main jack engaging portions and thereby the extent of movement of said main jacks.

37. In needle jack selecting and positioning mechanism for knitting machines, the combination of a needle jack, a push jack operatively related thereto, a connecting jack operatively engaging a portion of said push jack, a main jack, an interposed jack movable to and from operative position between said main jack and said connecting jack, a cross jack having laterally extending portions which engage said interposed jack, cam means engaging said cross jack, and means arranged and adapted to move said cam means in one direction to actuate said cross jack and thus displace said interposed jack from said operative position between said main jack and said connecting jack and in the opposite direction to return said interposed jack to operative position.

38. In a knitting machine wherein the needles are conditioned for knitting or for idling in any course by the positioning of needle jacks and push jacks operatively related thereto; and means are provided for adjusting the push jacks in one direction to effect conditioning of said needle jacks for idling and in another direction to effect conditioning thereof for knitting, the combination of jack means movable in a direction across the path of movement of said adjusting means into and out of operative relation thereto, said jack means comprising a slidably mounted cross jack and an interposed jack engaged by said cross jack and movable therewith in said direction across the path of movement of said adjusting means, and movable in relation thereto in the direction of movement of said adjusting means.

39. In a knitting machine wherein the needles are conditioned for knitting or for idling in any course by the positioning of needle jacks and push jacks operatively related thereto; and means are provided for adjusting the push jacks in one

5

direction to effect conditioning of said needle jacks for idling and in another direction to effect conditioning thereof for knitting, the combination of jack means movable in a direction across the path of movement of said adjusting means into and out of operative relation thereto, said jack means comprising a slidably mounted cross jack having spaced laterally extending lugs, and an interposed jack slidably engaged with said cross jack between said lugs and movable with endwise movement of said cross jack into and out of operative relation to said push jack adjusting means.

40. In needle jack selecting and positioning mechanism for knitting machines, the combination of a push jack, a connecting jack arranged to engage a portion of said push jack, means for moving said connecting jack in one direction to effect angular adjustment of the push jack, said means including a main jack operatively related to said connecting jack, a lifting plate adjustable to and from a position wherein a portion thereof is operatively related to a portion of said main jack, selector means movable to different positions of adjustment, means for moving said selector means toward and from said lifting plate when at any of said positions of adjustment, and a fashioning bar interposed between said selector means and said lifting plate and having a portion arranged and adapted to engage said lifting plate and other portions arranged and adapted to be engaged by said selector means at different distances from said edge portions, whereby when said fashioning bar is lifted by the selector means, said lifting plates and said main jacks may be moved to different extents depending on the position of adjustment of the selector means in relation to the fashioning bar.

THOMAS S. HAYHURST.
